UNITED STATES PATENT OFFICE.

JOHN F. JARRELL, OF DELTON, VIRGINIA.

DESIGN FOR A TOY.

51,924.

Specification for Design.

Patented Apr. 2, 1918.

Application filed March 3, 1917. Serial No. 152,409. Term of patent 14 years.

To all whom it may concern:

Be it known that I, JOHN F. JARRELL, a citizen of the United States, residing at Delton, in the county of Pulaski and State of Virginia, have invented a new, original, and ornamental Design for a Toy, of which the following is a specification, reference being had to the accompanying drawing, forming part thereof.

Figure 1 is a perspective view of the toy; and

Fig. 2 is an end view.

I claim:—

The ornamental design for a toy as shown.

JOHN F. JARRELL.

Witnesses:

I. I. RIGNEY.

ERNEST RIGNEY.
